COMBINED COMB AND SHEATH THEREFOR

Hazelle J. Kirkpatrick, 3645 NW. 17th Ave.,
Miami, Fla. 33142

Filed Dec. 11, 1972, Ser. No. 314,236

Term of patent 7 years

Int. Cl. D28—03

U.S. Cl. D86—8

FIG. 1

FIG. 2

FIG. 4

FIG. 1 is a top plan view of a combined comb and sheath therefor showing my new design.

FIG. 2 is a bottom plan view.

FIG. 3 is an edge elevation view.

FIG. 4 is an end elevational view; and

FIG. 5 is an exploded perspective view.

I claim:

The ornamental design for a combined comb, and sheath therefor, substantially as shown.
